CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE CORE-BARREL FOR CORE-DRILLS.

1,383,939.

Specification of Letters Patent. Patented July 5, 1921.

Application filed August 3, 1920. Serial No. 401,000.

To all whom it may concern:

Be it known that I, CHARLES C. HANSEN, a citizen of the United States, residing at Easton, in the county of Northampton and 5 State of Pennsylvania, have invented a certain new and useful Improvement in Double Core-Barrels for Core-Drills, of which the following is a specification.

This invention relates to core barrels for 10 core drills, but more particularly to a double core barrel for use with a shot bit.

The primary object of the invention is to enable the shot and cleaning fluid as 15 water to be introduced through the usual hollow drill rod and carried downwardly through the space between the outer and inner core barrels to the cutting edge of the bit, without coming in contact with the core, which is protected by the inner core barrel.

20 Another object of the invention is to provide means for slidably and loosely mounting the inner core barrel on a support within the outer core barrel at its lower end and on a core barrel plug at its upper end and 25 permit the shot and water to pass through lateral openings in the bit above the inner core barrel support to the cutting edge so that the shot and water pass around the outside of the bit to the cutting edge.

30 Another object of the invention is to provide a relief valve which controls communication between the inside of the inner core barrel and the space between the barrels for equalizing the pressure above the core, as 35 the core is gradually extended up into the inner core barrel.

To all of these ends the invention is shown in one of its preferred forms in the accompanying drawings in which—

40 Figure 1 is a vertical sectional view of a double core barrel embodying the invention in the act of cutting the core, with the hollow drill rod omitted for simplicity,

Fig. 2 is a detail sectional elevation showing the core after it has been broken,

Fig. 3 is a transverse sectional view on the line 3—3 of Fig. 1, and

Fig. 4 is a transverse sectional view on the line 4—4 of Fig. 1.

50 Referring to the drawings, A represents the outer core barrel having the shot bit B connected thereto at its lower end and provided with a series of lateral openings C for the passage of shot and cleaning fluid 55 as water to the cutting edge of the bit.

A core barrel plug D having the bore E in its upper portion is connected to the upper end of the outer core barrel A and extends within the said barrel. This core barrel plug is adapted to be connected to 60 the usual hollow drill rod (not shown).

A core barrel support F in the form of an annular ring is mounted in the upper portion of the bit B substantially below the lateral openings C. This core barrel support is preferably provided with a beveled upper edge G and a shoulder H, upon which shoulder the inner core barrel J is loosely mounted or supported. The upper end of the inner core barrel J is slidably supported 65 and guided by the downwardly extending portion K of the plug D.

70 Radial passages L lead from the bore E of the plug D to the space O between the inner and outer core barrels so that shot and water introduced into the bore E of the plug D are carried outwardly by centrifugal force by the passages L and pass 75 downwardly in the space between the outer and inner barrels to the aperture C and 80 thence pass downwardly through the grooves P in the outside of the bit to the cutting edge. In this way the shot and water do not come in contact with the core Q. A core lifter R of the usual form may be provided in the bit and the core is shown broken and in the act of lifting in Fig. 2.

85 A valve chamber S is provided within the lower end of the core barrel plug D and communicates with the space between the outer and inner core barrels by means of the passages T. A valve cage U is shown in this instance as screw threaded into the lower end of the plug and provided with 90 passages V leading from the space within the inner core barrel J to the valve chamber S. A relief valve W seats over the end of the cage U and controls communication between the inner core barrel and the valve chamber. This valve is normally maintained closed by means of the spring X. The function of the relief valve W is to 95 equalize the pressure above the core, as the core is gradually extended up into the inner core barrel.

100

I claim—

1. A double core barrel for core drills comprising outer and inner barrels, a bit connected to the lower end of the outer barrel, a plug connected to the upper end of 110

- said outer barrel, the said plug having an upper bore communicating radially with the space between the barrels, a valve chamber below said upper bore, a relief valve in said chamber controlling communication between the inner barrel and the space between the barrels, and lateral apertures in the upper portion of the bit, whereby shot and cleaning fluid introduced into the plug are carried by centrifugal action into the space between the barrels, and pass downwardly and out through the said lateral apertures and around the outside of the bit to the cutting edge.
5. A double core barrel for core drills comprising outer and inner barrels, a bit connected to the lower end of the outer barrel, a plug connected to the upper end of the outer barrel, the upper portion of said plug having a bore to receive shot and liquid and a support for the lower end of the inner barrel also forming a closure for the annular space between the barrels, and arranged below a series of lateral openings in the upper portion of the bit through which shot and cleaning fluid pass around the outside of the bit to the cutting edge, passages leading from the bore of the plug to the space between the barrels, a valve chamber in the lower portion of the plug, and a relief valve in said chamber for controlling communication between the inside of the inner barrel and the space between the barrels.
3. A double core barrel for core drills comprising an outer barrel, a plug connected to said barrel at its upper end and extending within the barrel, the upper portion of said plug having a bore adapted to communicate with a hollow drill rod, and a shot bit carried by said barrel at its lower end and provided with lateral openings, a core barrel support within the bit arranged below the said openings, an inner barrel loosely mounted on said support and slidably guided at its upper end by the lower end of the core barrel plug, passages leading from the bore of the plug to the space between the outer and inner core barrels for the introduction of shot and cleaning fluid to the bit, a valve chamber in the lower end of said plug communicating with the interior of the inner barrel and with the space between the barrels, and a relief valve controlling communication between the interior of the inner barrel and the said valve chamber.
4. A double core barrel for core drills comprising outer and inner barrels, a bit connected to the lower end of the outer barrel, a plug connected to the upper end of the outer barrel, an annular member in said bit supporting the inner barrel and closing the space between the outer and inner barrels, said bit having a series of exteriorly directed lateral apertures leading from the space between the barrels above said annular member, the upper portion of said plug having a bore to receive shot and liquid and passages leading to the space between the barrels, whereby shot and liquid introduced into the plug are carried by centrifugal action into the space between the barrels, downwardly, and through the lateral apertures to the outside of the bit and from thence to the cutting edge.
5. A double core barrel for core drills comprising outer and inner barrels, said inner barrel consisting of an open-ended cylinder, a bit connected to the lower end of the outer barrel, an annular member in said bit supporting the inner barrel and closing the space between the outer and inner barrels, said bit having a series of exteriorly directed lateral apertures leading from the space between the barrels above said annular member, a valve chamber in the lower portion of said plug communicating with the interior of the inner barrel and with the space between the barrels and a relief valve controlling communication between the interior of the inner barrel and the said valve chamber, the upper portion of said plug having a bore to receive shot and liquid and passages leading to the space between the barrels, whereby shot and liquid introduced into the plug are carried by centrifugal action into the space between the barrels, downwardly, and through the lateral apertures to the outside of the bit and from thence to the cutting edge.
- In testimony whereof I have signed this specification.

CHARLES C. HANSEN.
